G. M. MARKS.
Sulky-Plow.

No. 228,659.

Patented June 8, 1880.

UNITED STATES PATENT OFFICE.

GEORGE M. MARKS, OF FOWLER, PENNSYLVANIA.

SULKY-PLOW.

SPECIFICATION forming part of Letters Patent No. 228,659, dated June 8, 1880.

Application filed December 8, 1879.

To all whom it may concern:

Be it known that I, GEORGE M. MARKS, of Fowler, in the county of Centre and State of Pennsylvania, have invented certain new and useful Improvements in Sulky-Plows; and I do hereby declare that the following is a full, clear, and exact description of the invention, which will enable others skilled in the art to which it appertains to make and use the same, reference being had to the accompanying drawings, which form a part of this specification, and in which—

Figure 1 is a plan or top view of a sulky-plow embodying my improvement. Fig. 2 is a side elevation of the same. Fig. 3 is a rear elevation; and Fig. 4 is a sectional view through line $x x$, Fig. 3, showing the wheel-adjusting devices.

Similar letters of reference indicate corresponding parts in all the figures.

My invention has relation to sulky-plows; and it consists in the improved construction and combination of parts, as hereinafter more fully described, and particularly pointed out in the claim.

In the drawings, A is the central beam, and A' A' the converging side pieces of the sulky-frame, the diverging rear ends of which are united by an upper and a lower cross-piece, B C, to which they are securely bolted. D is the driver's seat, which is secured upon the rearwardly-projecting end of the middle beam by a spring standard or bracket, d.

E E are the plow-beams, (two or more in number,) which are made of wood or iron, of a curved shape, as shown in the drawings, with their forward ends pivoted between the converging ends of the pieces A' A' upon a bolt, a, their rear ends carrying the shovels E' E', which may be of any desired size, shape, or construction.

F F are elbow-levers, each of which has its fulcrum in a short standard, b, upon the upper cross-piece, B. f is a rod or chain which connects the upper short arm of each of the elbow-levers F with one of the plow-beams, E, so that by operating the long arm of lever F the beam, with its shovel, is raised or lowered. It may be retained in this elevated position by means of hinged catches e e, which lock the levers F in place in their depressed position.

Each of the wheels G G has a square stub-axle, H H, which is inserted through hang-

ers h h, projecting downward from and bolted upon the lower cross-piece, C, of the sulky-frame. Bolted upon each of the stub-axles H H, between its pair of hangers h h, is a flattened rod or strap, I, which passes up through slots in the upper cross-piece, B, and is secured at its upper end in a lever, K, having its fulcrum in the front side of the cross-piece B at c.

The adjustable standards or bars I I have notches i^2 on one side, to engage with the pivoted pawls i i, by means of which said standards may be held in any given position.

From the foregoing description, taken in connection with the drawings, the operation and advantages of my improved sulky-plow will readily be understood.

The shovels may be set at any desired pitch and depth in the ground simply by operating the levers F F, either by the hands or feet of the driver, and the wheels are adjustable in like manner by operating levers K K, all the levers being within easy reach of the driver's seat.

By this construction the plows can be elevated so as to pass over stumps and other obstructions in the field, and the sulky-frame may be tilted by operating one of the levers K, so as to be used for hill-side plowing with the same ease and facility as for level plowing. Hence my improved plow is adapted for any kind of ground and any condition of soil, and as the frame consists of few parts simply put together, it is not liable to break down or get out of order, even with the roughest usage.

Having thus described my invention, I claim and desire to secure by Letters Patent of the United States—

In a wheel-cultivator, the combination of the axle C and the two pairs of guide-hangers h h with the wheel-spindles H H, the sliding bars I I, having notches i^2 , the levers K K, passing through the bars I, the pawls i i, and the frame A B, substantially as shown and described.

In testimony that I claim the foregoing as my own I have hereto affixed my signature in presence of two witnesses.

GEO. M. MARKS.

Witnesses:

HENRY L. BECK,
SAMUEL HOOVER.
